UNITED STATES PATENT OFFICE

93,880

DESIGN FOR A CHEWING GUM CARTON

John McCollum, New York, N. Y.

Application March 9, 1934, Serial No. 50,992

Term of patent 14 years

To all whom it may concern:

Be it known that I, JOHN McCOLLUM, a citizen of the United States, residing at the Borough of Manhattan, in the city, county, and State of New York, have invented a new, original, and ornamental Design for a Chewing Gum Carton, of which the following is a specification, reference being had to the accompanying drawing, forming part thereof.

Fig. 1 is a perspective view of a chewing gum carton showing my new design.

Fig. 2 is a rear elevation thereof.

I claim:

The ornamental design for a chewing gum carton as shown.

JOHN McCOLLUM.
